UNITED STATES PATENT OFFICE

ANTON J. RAUS, OF CLEVELAND, OHIO

CLEANING APPARATUS

Application filed November 20, 1931. Serial No. 576,323.

My invention relates to an apparatus for cleaning hats of all description and is also available for cleaning wearing apparel.

One of the objects of the invention being 5 to provide a means by which any number of hats may be cleaned simultaneously, regardless of size. Another object is to provide an adjustable hat retainer.

Still other objects will be noted from the 10 following description and accompanying illustrations, and in which:

Fig. 1 is a side elevation partly in section of the apparatus; Fig. 2 is a transverse section taken on line 2—2 of Fig. 1; Fig. 3 is an 15 enlarged section of the apparatus with the hat retaining frame plate in collapsed position; Fig. 4 is a greatly enlarged rear end partly in section with the hat retaining frame plate in open position; Fig. 5 is a section 20 view similar to Fig. 4 with the portable fin in position for cleaning articles other than hats; Fig. 6 is an enlarged fragmentary section of the rotating basket and gears; Fig. 7 is a bottom plan view of the rim plate and 25 adjustment band; Fig. 8 is a longitudinal section of Fig. 7; Fig. 9 is a fragment of the adjustment band in perspective; Fig. 10 is a perspective view of the locking device by 30 which the rim plate is attached to the frame plate; Fig. 11 is a fragment of the rear end plate of the revolving basket, showing the apertures through which the fins are inserted 35 in the basket stave; Fig. 12 is a greatly enlarged section of the floating guide and roller; Fig. 13 is a longitudinal section taken on 40 line 13—13 of Fig. 12; Fig. 14 is a fragmentary section of the top basket stave and hinged section; Fig. 15 is a detailed plan view of the top basket stave and hinged section.

Referring specifically to the drawings:— the numeral 10 indicates the stationary lower portion of a tank with top cover sections 11 and 12 hinged at 13 to the ends of the tank 45 and sides 14 and 15 hinged at 16 to the sides of the tank and held closed with latches 17, and a drive shaft 18 mounted through the end pieces of the stationary tank 10, and rotating in bearings 19 and 20.

50 A motor 21 is mounted on the cover section

12, with a shaft 22, upon which is mounted a gear 23 which drives a gear 24 mounted on the shaft 18 outside of the tank. A gear 25 mounted on the shaft 18, inside of the tank, drives a ring gear 26 bolted to the rear end 55 flanged plate 27 of the revolving carrier or basket 28.

The revolving carrier or basket 28 comprises opposite or upper and lower staves 29, with undercut grooves 30 for the floating or 60 sliding guides 31 and rollers 32; a plurality of staves 33 with a pair of anchor straps 34 mounted rearwardly on the staves 33, auxiliary staves 35 and 35a mounted at each side of staves 29 and 33 and upon which the hinges 36 and latches 37 are mounted, to permit each section of the carrier cylinder to be opened or closed when filling or removing articles 65 from the carrier. Each cylinder section comprises or is covered with a fine mesh wire 70 screen 38 turned under the hoop 39 at each inside end of the front and rear flanged plates 27a and 27 respectively, and also under the edge of the auxiliary stave 35a to allow the 75 section to open at that point.

Slidable within the stave 29 is a floating 80 guide 31 with a roller 32 rotating within the slot 40 in said guide and journaled on the pin 41 mounted through the guide 31. Said roller 32 causes the floating guide 31 to slide along the groove 30 in the stave 29 as the roller 32 moves along the upper groove or track 42 in the stave 29. Attached to the inner extended portion of the floating guide 31 is a hinge 43 attached to a plate 44 which in turn is mounted on a hat retaining frame plate 45 in such manner as to extend out from the frame plate 45; and mounted between each frame plate 45 are a set of hinges 46, 47 and 48 attached 85 at one end to a plate 44 and the other end to a hinge 43 and plate 44, as shown in Figs. 1, 2, 3, 4 and 6. The purpose of this arrangement of hinges is to allow the hat retaining frame plates 45 to be compressed or collapsed into approximately one half of the space in the tank 10, thus providing a space in which to 90 clean garments other than hats.

The hat retaining frame plate 45 has an inner grille or spider 49 which is joined to the frame plate 45 at a plurality of points, the 100

center of the grille forming a sleeve 50 through which a horizontal shaft 51 is slidably mounted. Attached to the grille 49 between the outer circumference of the frame plate 45 and the inner ring 49a of the grille is a circular ring 52 locked to the grille 49 at each cross bar by a hinged latch 53 as shown in Fig. 10, said latch being attached to the grille 49 by any suitable means. Connecting bars 54 are attached at regular intervals to the outer circumference of the frame plate 45 and the inner ring 49a of the grille and proportionate distances from the cross bars of the grille 49.

Mounted at the intersection of the cross bars of the grille 49 and the circular ring 52, and of the inner ring 49a and the connecting bars 54, are the hat holders comprising a rim plate 55 and adjusting band 56 and the rim plate 55 has a cross member 57 to which the cross member 58 of the adjusting band 56 is attached by bolts 59, and these may be fastened at the locking points of the above mentioned cross bars and connecting bars by means of center bolts 59a permanently mounted through the grille 49, connecting bar 54 and the inner ring 49a, under the hinge lock 53.

After a hat is inserted over the adjusting band 56 said band is adjusted to the correct head size by pivoting the finger plate 61 up from contact with the corrugations 62 in the adjusting band, drawing the knobs 63 and 64 together or apart as is necessary and again moving the finger plate 61 into the corrugations 62 by pivoting at 65. A guard 66 is attached to the smooth end of the adjusting band 56 by suitable means, such as bolting, the corrugated end of the adjusting band being free to move through the guard 66.

47 A block 67, preferably of a light weight metal, is attached to the adjusting band 56 by a plurality of straps 68 bolted at intervals through the apertures 69 in the adjusting band.

48 A rim spring guard 70 holds the hat 60 in position over the block by pressing the rim of the hat against the rim plate 55.

When cleaning other articles than hats the shaft 51 is drawn out through the hub 71, said hub rotating in the rearing 72 bolted to the tank 10, and thus causes the hinges 46, 47 and 48 to collapse, drawing the frame plates 45 forward. A screen 73 is bolted to the stop plate 74 mounted on shaft 51 and hinged to the hat frame plate 45 in the same manner as the other frame plates are joined. After the frame plates 45 are drawn together, forming an open space at one end of the tank 10, the pivoting covers 75 attached to the flanged end plate 27a are unbolted at 76 and pivoted upward at 77, uncovering apertures 78 in said plate 27a through which the blades or fins 79 are thrust into the grooves 80 in the staves 33 until one end enters the anchor straps 34 and these serve as projections

against which the objects to be cleaned are thrown by the revolving basket 28. Flanged plate 27 has an attached hub 81 which revolves in bearings 82 bolted to the tank 10.

In operation, the tank 10 is filled below the bearings 71 and 81 with a cleaning fluid, the cylinder sections raised at each side, hats or other articles to be cleaned are placed on their respective holders, the sections are then closed, the motor is started, and the gears in turn revolve the carrier or hats through the liquid.

80 In use the hinge latch 53 closes its flaps 82 and 83 inward, each flap being pressed over a pin 84 which projects through the apertures 85 in said flaps. A discharge pipe 86 and shut-off 87 allows the used fluid to be removed after the cleaning process is finished.

85 When used to clean articles other than hats, the carrier is collapsed as shown in Fig. 3 and the articles are placed in the end space thus formed in the carrier which is then rotated in the liquid, the blades or fins 79 acting to agitate the articles as they are tumbled in the cleaning fluid.

90 While I have shown this invention as embodied in a particular form, yet I do not wish to be limited to this exact form, as it is evident that modifications can be made in the shape and proportions of the device and in the details of construction without departing from the spirit of this invention or the scope of its claims.

I claim:

1. In a cleaning apparatus, in combination, 100 a tank for liquid, and a rotary carrier in said tank, and a series of axially spaced annular frames extending across said carrier and around the axis thereof, each frame being provided with a plurality of article holders on the side thereof.

105 2. The combination stated in claim 1, each article holder including a ring to fit within a hat.

110 3. The combination stated in claim 1, each article holder including a form to fit within a hat, and an outer ring fitting around the brim of the hat.

115 4. In a cleaning apparatus, in combination, a tank for liquid, and a rotary article carrier in said tank, said carrier having therein a plurality of axially shiftable frames having article holding means thereon to provide space in one end of the carrier for other articles when desired.

120 5. The combination stated in claim 4, said carrier including a shaft, and the frames being slidable along said shaft to collapsed position.

125 6. In a cleaning apparatus, in combination, a tank for liquid, a rotary perforated container mounted on a shaft therein, said container having guideways extending lengthwise thereof, and a series of axially shiftable frames having article holding means there-

on and slideable lengthwise on the shaft and having peripheral guides in said guideways, whereby said frames may be collapsed into one end of the container.

5 7. The combination stated in claim 6, and flexible connections between the respective frames, foldable to permit collapse of the frames.

10 8. In a cleaning apparatus, in combination, a tank for liquid, a rotary horizontal perforated cylinder in the tank, and a series of spaced article holding frames in the cylinder, each frame including a vertical spider extending across the cylinder, and a plurality of article holders mounted on the side of each spider.

15 9. The combination stated in claim 8, the cylinder having elongated staves supporting the arcuate wall thereof, and the spiders having peripheral engagement with said staves.

20 10. The combination stated in claim 4, and means extending outside the tank to collapse or expand said frames in the carrier.

25 In testimony whereof, I do affix my signature.

ANTON J. RAUS.
